Primary Examiner — Jennifer Rivard*Assistant Examiner* — Jennylou M Binas(74) *Attorney, Agent, or Firm* — Addison D. Ault; Richard P. Moerschell; IPG Gentleman Intellectual Property Services, LLC(57) **CLAIM**

The ornamental design for a vacuum, as shown and described.

DESCRIPTION

FIG. 1 is a perspective view of a vacuum showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

(Continued)

The broken lines shown in the figures depict portions of the vacuum that form no part of the claimed design.

1 Claim, 7 Drawing Sheets
